UNITED STATES PATENT OFFICE.

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

DRILL SHARPENER.

Application filed November 11, 1925. Serial No. 68,447.

This invention relates to drill sharpeners, but more particularly to a drill sharpener in which a pair of posts are secured to the forging piston for supporting the cross head.

5 The object of the invention is to guide the free ends of the posts and to provide rigidity to said posts.

Other objects will be in part obvious and in part pointed out hereinafter.

10 The invention consists of the combinations of elements, features of construction, and arrangement of parts having the general mode of operation substantially as hereinafter described and more particularly pointed out 15 in the appended claims and illustrated in the accompanying drawings, in which

Figure 1 is an elevation partly in section of a two-post drill sharpener illustrating the manner in which the free ends of the 20 posts are guided,

Figure 2 is a side view in elevation of the top portion of the drill sharpener,

Figure 3 is a transverse sectional view taken through Figure 1 on the line 3—3 25 looking in the direction of the arrows,

Figure 4 is an elevation partly in section of the top portion of a drill sharpener illustrating a modified manner of guiding the free ends of the posts, and

30 Figure 5 is a top plan view of Figure 4. Referring to the drawings and more particularly to the preferred modification illustrated in Figures 1, 2, and 3, the sharpener indicated generally by A is provided with a hollow base B having formed integrally therewith a raising cylinder C. At the top of the base B is formed a lateral flange D which in this instance forms a support for an anvil block E. The anvil block E is 35 preferably secured to the flange D by means of bolts F and has formed integrally therewith at its lower portion a clamping cylinder G. Within the clamping cylinder G is arranged a reciprocating clamping piston H 40 which carries a reduced extension forming a poston J extending into the raising cylinder C.

Arranged above the anvil block E is a cross head K supported by a pair of posts 45 L which in turn are supported by the piston H and in this instance secured thereto by means of nuts O. The posts L may be press-fitted or secured in any other suitable manner in the crosshead K. The nuts O are 50 preferably of somewhat greater length than

the portion of the posts upon which they are screwed so that they may receive recessed 60 plugs P which may be forced firmly against the ends of the posts and thus serve to hold the nuts O securely in position.

The posts L are preferably so spaced with respect to the raising cylinder C that during the reciprocation of the piston H, the nuts O will pass freely along the side of said raising cylinder. By means of this arrangement free access may be had to the nuts O at all times, and the posts L or any associated parts may be readily removed from the machine without disturbing the general assembly of the machine.

70 The admission of pressure fluid to the raising cylinder C and the clamping cylinder G is preferably controlled by a controlling means such as that which is described in U. S. Patent No. 1,501,918 entitled Sharpener for drill steels, granted July 22, 1924 to myself and Mortimer S. Parkhill. Accordingly, a valve chest Q is secured to the side of the anvil block E in which a suitable valve (not shown) actuated by a lever R 75 may be reciprocated for controlling the admission of pressure fluid to the cylinders and the exhaust of pressure fluid therefrom in the manner described in the aforesaid patent.

75 In the adjacent faces S and T of the anvil block E and the cross head K respectively are formed recesses or die sockets U and V to receive forming dies such as for instance of the type which are used for forming the bit ends of drill steels. In this instance the anvil block E and the cross head K are provided with suitable extensions W and X having recesses Y and Z which are adapted to cooperate for clamping drill steels or other similar articles.

95 90 Usually in sharpeners of this type means are provided for forming the cutting faces or wings on the drill steel. Accordingly a pair of guides b (Figures 3 and 5) are secured to the machine to receive slidably a dolly cylinder c into which may be arranged the forming dolly (not shown).

100 105 In accordance with the present invention a guiding and protecting yoke d preferably having a plurality of downwardly extending legs e is arranged above the cross head K and is preferably secured to the anvil block E outside the periphery of the cross head by means of suitable bolts f. Formed in the yoke d are a pair of holes g into which 110

in this instance are inserted bushings *h* to receive the free ends of the posts which form guide members *L*. The yoke *d* is preferably of such a height that when the cross head 5 reaches the uppermost limit of its stroke, a slight clearance will exist between the cross head and the yoke as shown in Figures 1 and 2.

It will be observed from the foregoing description that the free ends of the posts *L* are at all times well guided and that flexing or bending of the posts is therefore prevented. By means of this invention the reciprocating elements of the machine will 10 be held against excessive side thrust and in consequence, these parts as well as the parts through which they reciprocate, will render satisfactory service for a considerably longer period of time than is the case in similar machines in which the posts are unguided at top ends.

In the modification shown in Figures 4 and 5, a yoke *j* is secured to the anvil block *E* for guiding and supporting the free ends 15 of the posts *L*. In this instance only a single leg *k* is provided at each end of the yoke, and the bottom face *o* and the inner face *p* of the legs are preferably machined to cooperate with correspondingly formed 20 notches or recesses *q* on the anvil block *E*. The yoke *j* may be secured to the anvil block in any suitable and convenient manner as for instance bolts *r* which extend through 25 lugs *s* carried by the legs *k* and through flanges *t* formed on the anvil block *E* and are provided with nuts *u* whereby the yoke 30 is clamped securely in position.

In order that the holes *g* in the yoke *j* may be properly aligned with the posts *L*, a tapered hole *v* is formed through one of the legs *k* and into the anvil block *E* to receive a dowel pin *w*, the small end of which is preferably screw threaded to cooperate 40 with corresponding threads *x* of the anvil block *E*. In this way the dowel pin *w* may be drawn firmly into position.

I claim:

1. In a drill sharpener, the combination of a hollow base formed with an integral raising cylinder having a lateral flange, an anvil block supported on said flange and having a clamping cylinder at its lower portion surrounding the raising cylinder, a clamping piston in said clamping cylinder having a reduced extension in said raising cylinder, a movable cross head above the anvil block, posts connected to the cross head and the clamping piston, the upper ends of the posts extending beyond the cross head to form guide members, a guiding and protecting yoke extending over the cross head and having legs supported upon the anvil block outside of the periphery of the cross head, the upper guiding ends of the posts extending into said apertures in the yoke.

2. In a drill sharpener, the combination of a hollow base formed with an integral raising cylinder having a lateral flange, an anvil block supported on said flange and having a clamping cylinder at its lower portion surrounding the raising cylinder, a clamping piston in said clamping cylinder having a reduced extension in the raising cylinder, a movable cross head above the anvil block, posts connected to the cross head and the clamping piston, the upper ends of the posts extending beyond the cross head to form guide members, a guiding and protecting yoke extending over the cross head and having legs supported upon the anvil block outside of the periphery of the cross head, the upper guiding ends of the posts extending into guide apertures in the yoke, the lower ends of the posts projecting through the clamping piston into recesses in the base, and securing means on said lower ends accessible from the outside of the base due to said recesses in the base.

In testimony whereof I have signed this specification.

ARTHUR E. PETERS.
